US00D573599S

(12) United States Design Patent
Williams

(10) Patent No.: US D573,599 S
(45) Date of Patent: * Jul. 22, 2008

(54) GRAPHICAL USER INTERFACE FOR A PORTION OF A DISPLAY SCREEN

(75) Inventor: Allan Williams, 143 Castle Glen Crescent, Ottawa, Ontario (CA) K2L 4G9

(73) Assignee: Allan Williams, Kanata, Ontario (CA)

() Term: 14 Years

(21) Appl. No.: 29/205,448

(22) Filed: May 5, 2004

(51) LOC (8) Cl. 14-04

(52) U.S. Cl. D14/486

(58) Field of Classification Search D14/485-95; D18/24-33; D19/6; D20/11; D21/324-33; 715/700-867

See application file for complete search history.

(57) CLAIM

The ornamental design for graphical user interface for a portion of a display screen, as shown and described.

DESCRIPTION

The single FIGURE is a front view of graphical user interface for a portion of a display screen showing the new and ornamental design.

The broken line showing of a portion of a display screen is for illustrative purposes only and forms no part of the claimed design.
